[57] ABSTRACT

A resilient sealing member, for use in an expansion joint, comprising serrated or dentate top and bottom walls and opposite side walls forming a hollow strip. An internal reinforcing network is provided in the hollow strip and comprises a plurality of web sections defining spaces therebetween into which the web sections may collapse when the side walls of the strip are pressed toward each other.

SEALING MEMBER

BACKGROUND OF THE INVENTION

This invention relates to seals for use in pavement or building joints, and is particularly concerned with pre-formed sealing strips or members adapted to be inserted in the grooves of expansion joints in, for example, a bridge deck.

It is necessary that expansion joints be used in pavements and the like to allow for expansion and contraction of a given length and/or width of pavement under varying temperature conditions and thus prevent buckling. Such joints are often grooves formed between adjacent pavement sections but may be spaces left between adjacent sections, or even grooves cut in the exposed surface of a pavement or the like.

In pavements such as roads and bridge decks these joints must be sealed in order to prevent accumulation of unwanted particles such as sand, gravel, and dirt and to prevent the infiltration of water which in cold weather freezes and may cause displacement and/or cracking of the adjacent pavement sections by freezing in the joints. For many years, it had been the practice to fill these grooves with a semi-solid filler or sealant such as asphalt or an elastomer-based caulking compound which would yield to permit expansion of the adjacent pavement sections. Because of the failure of these fillers to properly adhere to the side walls of the adjacent pavement sections, especially during the contraction of such sections, and because of a tendency toward brittleness at low temperatures, these joint fillers have permitted the ingress of water and foreign particles which ultimately damage the joint and the adjacent pavement sections. As a result, to maintain the pavement adequately, such joints have required frequent inspection and the filler has had to be repaired and/or replaced frequently.

In recent years, preformed compressible and expandable elastomer sealing members or strips of indeterminate length have been gaining acceptance and have gradually replaced the caulk-type fillers such as asphalt. Although these known preformed sealing strips have a relatively longer useful life and provide better sealing than the caulk-type fillers, they too have certain limitations. For example, there is a tendency, especially in bridge expansion joints wherein the seals are subjected to extreme stresses not only by compressive forces but also by vertical forces resulting from vertical displacement of the adjoining bridge sections, for the top edges of the side walls of the sealing strips to rotate upwardly and away from the facing surfaces of the adjoining sections. Also, in some sealing strips having internal networks of diagonally extending webs, these webs often bulge or fold excessively during compression. After long periods of maximum compression, such as might occur in hot summer months during which the pavement sections are continually expanded, the elastic properties of these webs are adversely affected and the webs tend to take a permanent set so that total recovery is not realized, thereby reducing the useful life of these sealing strips.

SUMMARY OF THE INVENTION

In the sealing strip or member of the present invention, as hereinafter described, the above-mentioned deficiencies are obviated by providing specially configurated top and bottom walls and an internal reinforcing

5 network comprised of a series of webs or struts arranged in a symmetrical pattern which prevents rotation of the side wall strip edges away from the adjoining paving sections and raises portions of the top wall of the strip during compression of the strip in use.

10 Generally speaking, the sealing strip of the present invention comprises a pair of parallel side walls joined together at their tops and bottoms by serrated or dentate top and bottom walls to form an elongated, hollow body. The strip is provided with a symmetrical internal reinforcing network of webs for effecting an equalization of sealing pressure at the strip side walls. These webs define various shaped cavities or spaces therebetween into which the webs are displaced during compression of the sealing strip and are interrelated in such a manner as to prevent rotation of the top and bottom edges of the strip side walls away from the facing surfaces of the adjacent pavement sections. Also, these internal webs cause upward movement of portions of the strip top wall to eject foreign matter accumulated in the joint above the sealing strip.

BRIEF DESCRIPTION OF THE DRAWING

20 FIG. 1 is an end elevational view of a sealing strip constructed in accordance with the present invention and shown in the uncompressed state;

25 FIG. 2 is a fragmentary top plan view of the sealing strip shown in FIG. 1;

30 FIG. 3 is a fragmentary sectional view of the joint between two adjacent pavement sections, showing a sealing strip according to this invention between said sections in a compressed state; and

35 FIG. 4 is a fragmentary, enlarged, end elevational view of the sealing strip of FIG. 1, illustrating some of the internal forces resulting from compression of the sealing strip.

DETAILED DESCRIPTION OF A PREFERRED EMBODIMENT

40 Referring to FIG. 1 of the drawings, it will be seen that a preferred embodiment of this invention comprises an elongated sealing strip, comprehensively designated 10, comprising a serrated or dentate top wall 11, a serrated or dentate bottom wall 12, and a pair of substantially parallel, vertical, essentially flat side walls 13 and 14 connected at their upper and lower edges to the top wall 11 and the bottom wall 12, respectively. The sealing strip 10 is conveniently formed of a suitable elastomeric material by extrusion molding. A neoprene composition that retains flexibility and resilience over a wide temperature range is usually preferred. It will be understood that the sealing member 10 may vary in length, as desired, and that such members may be of various widths so long as the height of the member varies proportionately to maintain a height to width ratio similar to that shown in FIG. 1.

45 The top wall 11 comprises a pair of outer sloping portions 15 and 16 extending inwardly and downwardly from the side walls 13 and 14, respectively, and forming therewith a pair of upper rounded corners 18 and 19 projecting above the main portion or body of sealing strip 10. A pair of intermediate sloping portions 20 and 21 extend inwardly and upwardly, respectively, from the lower ends of sloping portions 15 and 16, thereby forming grooves 22 and 23. A pair of inner sloping portions 25 and 26 extend inwardly and downwardly from the upper ends of the portions 20 and 21 forming api-

ces 27 and 28 therewith. The inner sloping portions 25 and 26 converge to form a groove 30. In the uncom-pressed state of the sealing strip 10, as shown in FIG. 1, it will be seen that the apices 27 and 28 are disposed somewhat below rounded corners 18 and 19. It should be noted that the terms top, bottom, up, down, right, left and similar terms of position or direction as used herein refer to the illustration in FIG. 1, but they are used only for convenience of description and should not be construed as limiting the scope of the present invention or as implying a necessary positioning of the structure or portions thereof.

The bottom wall 12 is substantially a mirror image of the top wall 11 and comprises outer sloping portions 31 and 32 that extend inwardly and upwardly from the side walls 13 and 14, respectively, and form therewith a pair of lower rounded corners 33 and 34 that project below the body of the sealing strip 10. Intermediate sloping portions 36 and 37 extend inwardly and downwardly from the upper ends of the portions 31 and 32 forming grooves 38 and 39 therewith. A pair of inner sloping portions 41 and 42 extend inwardly and upwardly from the lower ends of sloping portions 36 and 37 and form apices 43 and 44 therewith. The portions 41 and 42 converge to form a groove 45. The top, bottom, and side walls form an elongated tubular strip pro-vided with an internal reinforcing network of webs or struts as will presently be described.

Extending vertically downwardly from the grooves 22, 23 and 30, respectively, are a series of spaced, short, upper web sections 47, 48 and 49, which are sub-stantially parallel with each other and with side walls 13 and 14 and are in general vertical alignment with a se-ries of spaced, parallel, short, lower web sections 50, 51, and 52, respectively, that extend vertically up-wardly from the grooves 38, 39 and 45, respectively, in the bottom wall 12. Disposed between the upper and lower web sections 47 to 52, inclusive, in a side by side relation between the side walls 13 and 14 are three elongated cells extending longitudinally of the sealing strip and generally diamond shaped in cross section. These cells are bounded by inclined web sections as hereinafter explained.

The diamond shaped cell 53 on the right is bounded in part by a pair of inclined web sections 54 and 55 ex-tending downwardly and outwardly from the lower end of the upper vertical web 47 and terminating, respec-tively, in the side wall 13 at approximately the middle thereof, and at an intersection 56. A pair of inclined web sections 57 and 58 extend upwardly and outwardly from the upper end of the lower vertical web section 50 and terminate, respectively, in the side wall 13 at ap-proximately the midpoint thereof but below the web section 54, and at the intersection 56 to complete the cell 53.

The second, center, diamond shaped cell 59 is bounded in part by a pair of inclined web sections 60 and 61 extending downwardly and outwardly from the lower end of upper vertical web section 48 and termi-nating at the intersection 56 and an intersection 62, re-spectively, the latter intersection being laterally spaced from the intersection 56. A pair of inclined web sec-tions 63 and 64 extend upwardly and outwardly from the upper end of lower, vertical web section 51 and join the web sections 60 and 61 at intersections 56 and 62, respectively, to complete the center cell 59.

The third, left-hand, diamond shaped cell 65 is bounded in part by a pair of inclined web sections 66 and 67 extending downwardly and outwardly from the lower end of the upper vertical web section 49 and ter-minating, respectively, at the intersection 62 and in the side wall 14 at approximately the midpoint thereof. Completing the third cell 65 are a pair of inclined web sections 68 and 69 extending upwardly and outwardly from the upper end of the lower vertical web section 52, the web 68 joining the web section 66 at the inter-section 62 and the web 69 joining the side wall 14 at ap-proximately the midpoint thereof.

Additional elongated hollow spaces or cells extend-ing throughout the length of the strip 10 are formed by 15 the top, bottom, and side walls of the sealing strip 10, together with the reinforcing network of web sections. Cells 71, 72, 73 and 74, generally trapezoidal in cross section, are formed at the four corners of the sealing strip 10. A pair of side by side cells 76 and 77, hexago-nal in cross section, are provided in the upper central portion of the sealing strip 10 between the upper por-tions of the center diamond cross sectional cell 59 and cells 53 and 65, respectively. A pair of similarly shaped cells 79 and 80 are disposed in the lower central por-tion of the strip 10 between the lower portion of the cell 59 and the lower portions of the cells 53 and 65, respectively.

The sealing strip 10 is symmetrical about a horizontal plane X—X cut through the longitudinal axis of the 30 sealing strip 10 and a vertical plane Y—Y cut through such axis. This symmetrical design is important in equalizing the sealing pressure acting on the side walls 13 and 14. The intersections 56 and 62 act as pivot points about which the web sections on the right and left side of the plane Y—Y tend to pivot, respectively.

FIG. 1 illustrates the sealing strip 10 in its normal, un-compressed state prior to the intersection thereof in the slot or groove of an expansion joint. As shown in FIG. 3, the strip 10, in use, may be inserted in the slot 86 be-tween adjacent pavement slabs 87 and 88 such as are used in bridge decks. In many cases the adjacent cor-ners of the slabs are reinforced, as shown, by angle bars 90 embedded therein. Each angle bar 90 comprises a horizontal leg 91 disposed in the plane of the upper sur-face of the pavement slab and a vertical leg 92 extend-ing downwardly into the slot 86. The lower ends of the legs 92 are provided with inwardly projecting horizon-tal flanges 93 for support of the sealing strip 10.

The sealing strip 10 is of such width that it must be ini-tially compressed, usually to about 80 percent of its un-compressed width, to insert it between the opposite vertical legs 92 of the angle bars 90. Prior to inserting the sealing strip 10 into the groove 86, a coating of a suitable lubricant-adhesive is either applied to the ex-posed faces of legs 92 of the angle bars 90 and/or to the side walls of the sealing strip 10 to facilitate the inser-tion thereof in the groove and, when set, to cement the sealing strip 10 in place. Suitable lubricant-adhesives are well known and readily obtainable.

FIG. 3 illustrates the sealing strip 10 under substan-tial compression. As the sealing strip 10 is compressed from a slightly compressed condition to the condition shown in FIG. 3, the upper sloping portions 15, 16, 20, 21, 25 and 26 fold toward each other raising the apices 27 and 28 to dispel or eject large foreign bodies from the groove 86 above the sealing strip 10. The apices 27 and 28 reach a height approximating the level of the

rounded corners 18 and 19. Note, however, that the whole top wall 11 of the sealing member is always maintained below the level of the upper surfaces of the adjacent pavement slabs 87 and 88. Compression of the strip 10 also brings about corresponding outward movement of the lower apices 43 and 44.

Referring to FIG. 4, which illustrates a portion of the right side of the sealing strip 10 in uncompressed state, it will be seen that as the strip is compressed laterally, the web sections 54 and 57, respectively, exert force, indicated by arrows A, against the web section 55 at its juncture with web section 47 and against web section 58 at its juncture with web section 50. This causes pivoting of the web sections 55 and 58 about the intersection 56, thus tending to straighten them out into alignment with each other and with web sections 47 and 50, thereby preventing buckling of the webs and giving a controlled collapse of the sealing strip 10.

Furthermore, compressibility of the sealing strip 10 or collapsibility of the internal reinforcing web network into the spaces provided therein is better controlled because buckling of the web sections is eliminated. Also, due to the angular orientation of the web sections 54 and 57 relative to the side wall 13, the moment forces are equally distributed so as to prevent rotation of the side wall away from the interfacial surface of the adjoining angle bar leg 92 during compression and/or when a vertical force is exerted on the side wall 13 due to vertical displacement of the adjacent pavement sections. The forces exerted on the right side of the sealing strip 10, as shown in FIG. 4, are also applied to the left side thereof maintaining equal pressurization of both sides of the sealing strip 10.

The vertical plane of symmetry (Y-Y) of the sealing strip 10 insures equal sealing pressure along both side walls 13 and 14. It should also be noted that the sealing member 10 is reversible due to its horizontal plane of symmetry (X-X). An advantage residing in this feature is that the strip 10 may be inverted, if desired, in the event of damage to the top wall 11 during handling and installation of the sealing strip 10.

The present invention thus provides a new and improved sealing member for pavement joints having corrugated or dentate top and bottom walls and a novel, integral, reinforcing network of internal webs or struts 45 which is symmetrical in two planes and which provides equal sealing pressure along both side walls of the sealing strip. The configuration of this web network prevents buckling and overbending of the web sections and also causes the elevation of portions of the top wall to eject foreign matter from the joint above the sealing strip.

A preferred form of this invention having been herein described and illustrated in the drawings, it is to be understood that variations and modifications thereof can be made without departing from the spirit and scope of this invention, as defined in the appended claims.

We claim:

1. A seal for expansion joints comprising an elongated hollow strip having opposite side walls; a top wall 60

; and a bottom wall, the junctures of said side walls with said top wall and said bottom wall being rounded; and an integral, internal, reinforcing network of web sections, said network comprising a plurality of laterally spaced, upper web sections extending vertically downwardly from said top wall in generally parallel relation with said side walls, a plurality of laterally spaced, lower web sections extending vertically upwardly from said bottom wall in generally parallel relation with said side walls and substantial vertical alignment with said upper web sections, a plurality of generally diamond shaped cells including a centrally located cell disposed in a side by side relation between said side walls, each of said diamond shaped cells being bounded solely by a plurality of other web sections connected at their upper and lower ends, respectively, to one of said upper and one of said lower web sections, said central cell in cross-section being smaller than the others of said diamond shaped cells and symmetrical about a vertical axis, said strip being resilient and flexible and adapted, when subjected to pressure against said side walls, to be compressed whereby to narrow the width of said central cell and tend to straighten the web sections by which said central cell is bounded to provide increased support for the top and bottom walls of said strip.

2. A seal as defined in claim 1 wherein each of said diamond shaped cells is bounded solely by a pair of inclined web sections extending downwardly and outwardly from the lower end of one of said upper web sections and a pair of inclined web sections extending upwardly and outwardly from the upper end of the one of said lower web sections vertically aligned with said one upper web section, and joining the lower ends of said first pair of inclined web sections.

3. A seal as defined in claim 1 which comprises three generally diamond shaped cells, each cell being quadrilateral in cross section, one of said cells being disposed between the other two cells and joined thereto at laterally spaced intersections in said network.

4. A seal as defined in claim 1 wherein said top wall is serrated and comprises a plurality of transverse sloping portions, said sloping portions extending inwardly from said side walls and at their junctures defining grooves and apices.

5. A seal as defined in claim 4 wherein said apices are normally disposed below the upper edges of said side walls and are adapted to be raised upwardly, toward but no higher than the level of said side wall upper edges, upon lateral compression of said seal.

6. A seal as defined in claim 4 wherein the configuration of said top wall and said bottom wall are the same.

7. A seal as defined in claim 1 characterized by having two planes of symmetry, one horizontal and one vertical.

8. A seal as defined in claim 3 wherein said one of said cells has a smaller transverse width than said other two cells.
